METHOD OF AND APPARATUS FOR SHAPING
AND SIZING HATBRIMS

Gandolfe Cipriano, Dongan Hills, N. Y.

Application October 9, 1947, Serial No. 778,935

9 Claims. (Cl. 223—14)

The present invention relates to a method of and apparatus for shaping and sizing hat brims.

In the hat making industry, particularly that portion thereof which manufactures hats of felt, straw, or the like, large scale production and sale of hats having certain types or styles of brim have been retarded because of the excessive cost, due in large measure to the fact that, heretofore, brims of these types could be sized and shaped only by expensive hand operations. In making a "Homburg" style hat, for example, of felt or straw, the hat blank is formed by known procedures. The brim may vary in width; and its outer edge portions are rolled or bent to overlie intermediate portions. According to presently known practice, this rolling or bending of the edge and establishing of the final size and appearance of the brim are accomplished only by a series of hand operations performed by skilled and highly paid craftsmen in the hat ironing and finishing art.

Among the objects of my invention are the following: to provide a method whereby certain steps of the brim shaping and sizing procedure in making straw and felt hats may be performed at least in part mechanically and thereby reduce the time and the cost of the operation; to enable hat finishers to standardize certain brim shapes and sizes; to facilitate the sizing and shaping of the brims of hat blanks made from various materials, as different kinds of straws, felts and the like; and to provide procedure and apparatus whereby the brims of hat blanks of felt, straw, or the like, may be accurately sized and shaped to present inwardly rolled or bent edge portions.

In this specification and the accompanying drawings I have shown and described a preferred embodiment of my invention and suggested various modifications thereof; but it is to be understood that these are not intended to be exhaustive nor limiting of the invention but, on the contrary, are given for purposes of illustration in order that others skilled in the art may fully understand the invention and the principles thereof and the manner of applying it in various forms, each as may be best suited to the conditions of a particular use.

Other objects of and contemplated beneficial results flowing from the present invention will more clearly appear from the following description and the drawings appended thereto illustrating a preferred procedure and apparatus employed in practicing the method of said invention and wherein:

Figure 1 is a side elevation of a brim sizing

and shaping machine with portions thereof broken away and other portions shown in vertical section;

Figure 2, an enlarged fragmentary view in vertical section illustrating the relative positions of certain operating parts of the apparatus shown in Figure 1 but at a phase of operation subsequent to that there shown and early in the sizing and shaping of a roll edge brim;

Figure 3, an enlarged fragmentary view in vertical section of the parts shown in Figure 2, illustrating their relative positions at a later or intermediate size determining stage of the roll edge brim sizing and shaping procedure;

Figure 4, an enlarged fragmentary view in vertical section of the parts shown in Figures 2 and 3, illustrating their relative positions at the final phase of the roll edge brim sizing and shaping operation;

Figure 5, an enlarged fragmentary view in vertical section of modified brim sizing and shaping parts in relative positions prior to initiating certain portions of the sizing and shaping procedure wherein a form of brim edge differing from those shown in Figures 1 to 4, inclusive, is produced;

Figure 6, a view illustrating the final phase of the sizing and shaping procedure as performed by the parts shown in Figure 5;

Figure 7, an enlarged fragmentary view in vertical section of further modified brim sizing and shaping parts in relative positions prior to initiating certain portions of the sizing and shaping procedure for producing a type of welted brim edge with the welt or edge portion bent inwardly toward the top surface of the brim;

Figure 8, a view illustrating the final phase or stage of the sizing and shaping procedure as performed by the parts shown in Figure 7;

Figure 9, an enlarged fragmentary view in vertical section of a further modification wherein brim sizing and shaping parts are shown in relative positions obtaining at an early phase of the brim sizing and shaping procedure applied to produce a welt edge brim of the type with the edge or welt portion turned or bent back or inwardly toward the under surface of the brim, as distinguished from the style shown in Figure 8, for example, where the welt or edge is bent inwardly toward the top surface of the brim; and

Figure 10 is a view illustrating the final phase of the sizing and shaping procedure as performed by the parts shown in Figure 9.

U. S. Patent No. 1,991,921 describes and illustrates steps of method and an embodiment of apparatus for flanging hats, as by applying pressure

55

or heat and pressure to hat brims of the so-called finished edge or flat (not rolled) type. According to the present invention, the brim edge of felt or straw hats, or the like, when complete, takes the form of a roll, bend, or curve inwardly toward the crown by a procedure which includes the steps of applying pressure to portions of the brim between the crown and the peripheral edge, applying pressure to edge portions while the latter are in inwardly rolled or bent position, and applying to said edge and said intermediate portions of the brim greater pressure than that employed in said preceding steps. The foregoing operations, which are conveniently and advantageously, though not necessarily, performed by the mechanical means, hereinafter described, or equivalent means, follow a preparatory step wherein the brim is initially rolled or bent and edge portions thereof are simultaneously shrunk to less than the ultimate or finished maximum peripheral extent of the brim, thus producing an edge roll approximating the form indicated, for example, in Figure 5.

It will be understood that this pre-rolling of the brim will be applied to straw as well as to felt hat blanks and to blanks with untrimmed brim edges as well as to blanks, e. g., of the Panama type, with finished brim edges. Whether the brim of the blank be of the finished or unfinished type, the desired initial brim roll and edge shrink may be imparted thereto by any suitable means, as by the use of a curl or roll forming hand tool, known in the trade as a "shackle." At this stage, a hat is practically complete, except for the sizing and shaping of the brim and the application of trimmings, if any, as ribbons, hat bands, sweat bands, etc.

Where the brim, after pre-rolling, is brought to final size and shape according to my invention, the several steps of method involved are advantageously performed, at least in part, with the aid of devices to be described. One form of apparatus for the purpose includes a frame such, for example, as that shown in Figures 1 and 2 of said U. S. Patent No. 1,991,921, having uprights, tie members, a cross head sliding on said uprights, and devices for moving the cross head up and down, for example, a hand lever operatively connected to said cross head.

As seen in Figure 1 of the drawings appended hereto, a cross head 10 slides between predetermined up and down positions on uprights 11 and may be actuated by any suitable means, as a lever 12 which rotates shaft 12' so as to operate a toggle including arms 13 (one of which is shown) connected to shaft 12' and links 14 (one of which is shown) pivotally connecting said arms to cross head 10. Thus, cross head 10 is raised to "up" or inoperative position to insert or remove various interchangeable shape and size determining forms herein conveniently termed "irons" carried thereby and to permit the effective positioning of other irons adapted to cooperate therewith. Cross head 10 is moved to "down" position to bring said several irons into effective ironing or heating and pressing operation.

The irons carried by cross head 10 in a manner to be described are adjustable toward and from said cross head. For this purpose, a portion of cross head 10 is interiorly threaded to provide a nut 16 which receives the threaded boss 16a of a hand wheel 17. A central longitudinal hole 17a extends through boss 16a and hand wheel 17. An iron supporting plate 15 has a stem 15a which extends through said longitudinal hole 17a and

is provided at its upper end with a nut 15b. The under surface of nut 15b rides on a washer 15c which in turn rests on a portion of the top surface of hand wheel 17.

5 The arrangement is such that when said hand wheel 17 is turned in one direction, its boss 16a moves upwardly in nut 16. This lifts plate 15 and all parts supported thereon. Turning hand wheel 17 in the opposite direction lowers 10 said plate 15 and the parts supported thereon.

A pin 16b extending upwardly from plate 15 engages the slot of a slotted detent arm 16c extending laterally from nut 16. Thus, when hand wheel 17 is rotated, the tendency, if any, of plate 15 to like rotation is prevented by said pin 16b bearing against said fixed detent 16c.

20 A top iron 18, the uppermost of the several irons as they appear in Figures 1 to 4, inclusive, of the drawings, is releasably supported on a ring shaped frame 19, which is suspended from an intermediate ring 42 detachably secured to plate 15 by studs 20 and cotter pins 21. Hooks 22 and wing nuts 23 detachably hold the iron in position 25 in the carrier and heater frame 19. Counterparts of this structure are shown and more fully described in said Patent 1,991,921.

An electrical resistance heater element, as coil 24, or other suitable heating means with thermostatic and/or other suitable controls, such for 30 example as the three stage (low, medium and high) control switches shown in my said patent, supplies heat to said carrier ring 42, frame ring 19 and iron 18. Thus, when plate 15 is adjusted vertically by turning hand wheel 17, equivalent 35 adjustment of the position of iron 18 in relation to cross head 10 and other cooperating parts takes place. The above and other devices to be described, enable the operator to control the extent of pressure and heat to be applied to a 40 hat brim at different stages in the sizing and shaping thereof.

45 Apparatus for holding a hat blank in a position relative to iron 18, and other previously described parts, such that the brim may be sized and shaped according to the present invention includes a frame 25 having a handle 26 at one end, said frame being mounted to slide inwardly on table 27 from its outer position, as seen in Figure 1, to its inner, or operative position below iron 18. This table 27 is accurately positioned 50 on, or constitutes the bed of the toggle press which includes the parts 10 to 14, inclusive, above described. Below this table is shown a cabinet with shelves for holding hats, irons, etc., which 55 is a convenient arrangement and use for this space below the bed of the press.

A bottom iron 28, the lowermost of the several irons as they appear in Figures 1 to 4, inclusive, of the drawings, and which is supported on said 60 slidable frame 25, has an ironing surface, including a peripheral grooved portion 29. Said iron 28 is heated by suitable means such as a resistance element 30, or the like, with appropriate thermostatic and/or other controls such, for example, as the three stage switch control shown in my said patent and which provides low, medium or high heat at the will of the operator.

A middle or intermediate iron 31 is supported 70 in heat receiving relation to a ring 32 which is mounted to slide vertically and in telescoping relation to said bottom iron 28. Portions of the outer surface of iron 31 are normally in heat receiving relation to inner surface portions of iron 28. With the parts arranged as shown in Figure 75 4, i. e., during the final pressing stage, this heat

transferring area of contact is increased and iron 31 also engages and receives heat from frame 25.

To produce the desired sizing and shaping of brims of the roll or curl edge type, as in the Homburg style of hat, according to my invention, said irons 18, 28 and 31 are brought into operation in a predetermined order and under controlled conditions whereby they impart to the brim different degrees of pressure at different stages or phases of the method. This mode of operation is facilitated in the illustrated structures by the provision of springs of different compressive characteristics interposed respectively between various parts of the apparatus which are disposed between the cross head 10 and the slideable frame 25 when the parts are in operative position.

As seen in Figure 1, relatively heavy or stiff springs 34, four being employed in the illustrated embodiment, are interposed between the plate 15 and the ring 42 which carries frame 19 and iron 18. Relatively light or yielding springs 35 (also four in number) are interposed between portions of frame 19 and iron 18. These springs 35 are arranged and adapted to accommodate upward movement of the iron 18 in relation to frame 19 against gradually increasing resistance of said springs as they are shortened from extended condition, Figure 2, to compressed condition, Figures 3 and 4. Four medium heavy or stiff springs 36 are interposed between frame 25 and the iron carrying and heating ring 32 to yieldingly resist downward movement of said ring 32 and said iron 31 toward the frame 25 under circumstances, i. e., from their relative positions, Figure 2, to their relative positions, Figure 4, for a purpose to be described.

The extent of downward movement of iron 18 in relation to frame 19 by pressure of springs 35 is limited by pins 40 extending outwardly from said iron and into slots 41 in the wall of frame 19 and normally bearing against lower end portions of said slots. Thus, iron 18 is movable upwardly in relation to frame 19 against the relatively light resistance of springs 35; and iron 31 is movable downwardly in relation to ring 27 and frame 25 against the relatively greater resistance of the medium springs 36.

The extent of upward movement of ring 32 and hence of iron 31 due to springs 36 is limited by pins 37 extending inwardly from a portion of iron 28 into slots 38 in ring 32. These slots 38 are closed at their lower ends, as by a stop plate 39, which also normally engages said extended end portions of pins 37.

If it is desired to vary the effective resistance ratio between springs 34, 35, and 36 to conform to varying requirements of different materials or other characteristics of the hat brims being processed, springs of greater or less stiffness over a wide range may be employed, subject to the requirement that springs 36 shall be stiffer than springs 35, and that springs 34 shall be stiffer than springs 35 and 36.

The light springs 35 employed in the illustrated embodiment of the invention are conveniently 2 1/8 inches normal or open length. When fully compressed or closed, they are 1/2 inch long and exert a counterpressure of 2 1/4 pounds. The medium springs 36 are conveniently 2 3/8 inches normal or open length. When fully compressed or closed, they are 1 inch long and exert a counterpressure of 54 pounds. The heavy or stiff springs 34 are conveniently 1 3/4 inches normal or open

length. When fully compressed or closed, they are 7/8 inch long and exert a counterpressure of 120 pounds.

When employing apparatus as above described to carry out steps of the method included in the present invention, a hat, e. g., of straw, felt, or other material, and with its brim edge 43 pre-rolled or curled inwardly toward its crown 44, as previously described, is mounted, for example, as shown in Figures 1 and 2. In this case, the hat is to have a brim of predetermined final width with a permanent rolled or curled edge.

Ordinarily, in commercial operations, hat blanks of similar material and style will be processed in batches after the operator determines, in the case of each batch, approximately what pressure and temperature conditions are most effective to produce the desired result. In many cases the experienced operator will make the necessary adjustments without preliminary trial. In other cases, one or more hats may be ironed experimentally under different pressure and heat conditions. In general, if ironing a felt blank produces a shiny surface, the pressure is too great. As previously indicated, the pressures here referred to are adjustably controllable by turning hand wheel 17.

Having determined the approximately correct pressure and temperature conditions for blanks 30 having the particular characteristics of the illustrative example, and with carrier 25 in out position, the brim of each blank is initially positioned on iron 31, Figure 1, with its outer edge curled around a portion of the rounded rim of said iron 31. Frame 25 is then moved into position so that iron 31, with the brim disposed as indicated, comes into alignment below iron 18.

By pulling down on lever 12, the operator 40 brings iron 18 first to the position shown in Figure 2 where said iron comes into engagement with the hat brim supported on iron 31. At this point, irons 18 and 31 press relatively gently that portion 45 of the brim extending approximately from its rolled edge portion inwardly to where the brim joins the crown 44. Continued downward pull on lever 12 causes frame 19 to move downwardly in relation to irons 18 and 31, thus compressing the light springs 35 and, to that extent, gradually increasing the pressure of iron 18 on the brim portion 45 until springs 35 are compressed fully or to a predetermined maximum extent. In this phase, the medium springs 36 resist downward movement of iron 31 and the material of portion 45 of the hat blank brim is spread or extended smoothly and regularly between said irons 18 and 31 where it is held under yielding pressure without wrinkles or creases because of the application of gradually increasing pressure which allows undesired fullness to be pressed out. Figure 3 shows the relative positions of parts of the apparatus at the end of this phase of the operation and ready for the next phase, which comes with additional downward swing of lever 12.

Further actuating movement of lever 12 causes 70 further downward travel of frame 19 and iron 18. Since the springs 35 are now compressed to maximum extent, this further downward movement of frame 19 and iron 18 imparts like movement to iron 31 against yielding resistance of springs 36 which, as previously stated, are stiffer than springs 35; and with increasing compression of said springs 36 the parts are brought to the relative positions indicated in Figure 4, at

which stage, springs 36 are compressed fully or to a predetermined maximum extent.

In moving downwardly from the positions shown in Figure 3 to those shown in Figure 4, the irons 18 and 31 carry the curled edge portion 43 of the hat blank downwardly and into engagement with the groove 29 of bottom iron 28. Since the stiffer springs 36 are progressively compressed during this movement, pressure on the brim portion 45 is correspondingly increased in the second stage or phase just described; and the curled edge portion 43 is pressed between the rounded or curved under surface of the rim of iron 31 and the correspondingly curved surface of groove 29 in iron 28.

In the third phase, starting with the parts in substantially the positions shown in Figure 4, the final increment of actuating movement of lever 12 causes downward movement of plate 15 toward the intermediate plate 42 against resistance of the strong springs 34 which have yielded little, if any, in the steps previously described. However, in this final stage, as springs 34 are compressed, they impart increasing pressure to plate 42 and hence to the hat brim now engaged and pressed by the three irons 18, 31 and 28, Figure 4.

The amount of final pressure, the time during which it is applied and the concurrent heat and/or moisture conditions are likely to vary widely for different kinds of hats, depending upon such variable factors as the material, its thickness, its manner of fabrication, etc. With a given set of springs 34, 35, and 36 this final pressure will be controlled by adjusting plate 15 in relation to cross head 10. For example, if plate 15 is raised by turning hand wheel 17, the compressive effect of stiff springs 36 in the final step is diminished. Adjustment of plate 15 in the opposite direction, i. e., downward, produces increased final pressure.

Where circumstances require that the final pressure be applied and held for a measurable time, it will be convenient to swing lever 12 down to such extent that the toggle arms 13 (one shown) and the links 14 (one shown) come into substantially vertical alignment or just past that position, so that the cross head 10, the plate 15 and the irons 18 and 31 will in effect be releasably held in down position. Thus, the maximum required pressure may be maintained on the hat brim for any desired or necessary period of time. As seen in Figure 4, when the irons reach their final pressing position, there is a space between portions of the lower face of iron 31 and the upper face of iron 28 to accommodate the thickness of the material of the hat blank brim and permit application of the desired pressure thereto. If the peripheral edge of the brim, as finally sized and shaped, is irregular, the excess portions thereof will extend into this space and may be cut off in a later trimming operation after the hat has been removed from the machine.

In the modification shown in Figures 5 and 6, the hat to be processed is brought into operative position under iron 18a with its brim portion 45 supported on iron 31a. The brim curl or roll portion 43, pre-formed as previously explained, is then conveniently bent downwardly by hand to bring the free edge thereof into position between the under surface 31b of iron 31a and the upper surface 28b of iron 28a and engaging or lying opposite said surface 31b, or substantially as shown in dotted lines in Figure 5. As shown in Figures 2, 5 and 6, iron 31a, Figures 5 and 6, is

narrower than iron 31 of Figure 2; its top surface is more convex than the top surface of said iron 31; and the under surface 31b is flat as compared to the rounded under surface of rim portions of iron 31. These differences with others when utilized in accordance with the present invention produce a Homburg type brim quite different in appearance from that produced by operation of the irons in Figure 2, for example, although the sizing and shaping procedures are quite similar.

Considering further the modification shown in Figures 5 and 6 and its manner of use, it will be apparent that in the initial or preliminary shaping of brims of a given width the direction and extent of curvature of the brim and of its roll edge may vary considerably from that shown and with consequent greater or less initial conformity to the contours of the pressing surfaces of irons 18a and 31a. Nevertheless, when, in the first stage, iron 18a is moved down on a hat brim supported on iron 31a as shown in dotted lines, Figure 5, the material of intermediate portions 45 of the brim is pressed without creases or wrinkles between said irons 18a and 31a to approximately its final size and shape, commonly known as the "Homburg."

It is noted in connection with the parts shown only fragmentarily in Figures 2 to 6 inclusive, that the springs 34, 35 and 36, shown in Figure 1, are similarly disposed and perform the same functions in relation to the parts shown in said Figures 2 to 6 as they do in relation to corresponding parts shown more extensively in Figure 1.

In the modification shown in Figures 7 and 8, the iron 18b cooperates with an iron 31c which presents a somewhat sharply tapered peripheral edge as compared to the edges of the corresponding irons 31 and 31a previously described and as shown in Figures 2 and 5, for example. Iron 31c cooperates with an iron 28c having a flat upper surface which is substantially parallel to the flat lower surface of iron 31c.

This modified form of apparatus is employed to produce a welt edge brim with the rim portion bent back toward the hat body and overlying adjacent intermediate portions 45 of the brim.

As in the previously described procedures, the edge of the brim of the hat blank is pre-rolled or curled, as at 43, and when initially positioned on iron 31c for processing, overlaps and curls under the relatively sharp or attenuated outer rim of said iron. As the frame 19 is moved downwardly with plate 15, ring 42 and springs 34, it carries iron 18b into engagement with said brim portion 45 and causes that portion to be pressed against iron 31c without creases or wrinkles, the positions of the parts at this initial stage being approximately as shown in Figure 7. Inasmuch as the springs 36, Figure 8, are stiffer than the springs 35, continued downward movement of frame 19 will cause its lower rim portion 19a, Figure 7, to move downwardly past the outer edge of iron 31c and the rim portion thereon, there being sufficient clearance to accommodate the thickness of the brim material which overlaps said edge. As said lower rim portion 19a of frame 19 passes said edge of iron 31c, it wipes across the curl or roll edge 43 of the brim, causing said edge to bend inwardly so that portions thereof are brought between the bottom surface of iron 31c and the top surface of iron 28c. The edges

75 of said lower rim 19a, of said iron 31c, and of iron

28c engage said curl or roll 43 in operation and are preferably relieved or slightly rounded to facilitate operation and avoid injury to the hat blanks. After full or predetermined compression of springs 35 and after said lower rim 19a of frame 19 has bent the roll edge 43 inwardly, further downward movement of frame 19 carries said lower rim 19a thereof downwardly past the upper face of iron 28c and moves iron 31c toward said upper face of iron 28c against resistance of the stronger springs 36 and to the relative positions shown in Figure 8. Here, the curl or roll edge 43 is flattened, as indicated, and is fixed in said flattened condition in the final phase by pressure of springs 34 and the heated irons. If the inturned brim edge is irregular or does not satisfactorily conform to the outer brim contour, as established by the several irons, portions may be trimmed away after removal of the hat from the sizing and shaping devices.

A further modification, as in Figures 9 and 10, illustrates devices more particularly adapted to forming a hat brim with a relatively flat welt edge turned or bent inwardly toward or against the under surface of the brim (referring here to the normal position of a hat when worn). For this purpose, the iron 28d is mounted for limited vertical sliding movement in a recessed block 46, Figures 9 and 10, supported on table 25. Light springs 35a interposed between said iron 28d and said block 46 hold said iron in the normal or extended position, as seen in Figure 9, and wherein edge portions of the upper face of iron 28d extend above the top edge or rim 46a of said block. This extended or normal position is determined by the stop pins 37, inner end portions of which project into slots 38 and are engaged by a suitable detent, such as a stop plate 39 on said iron 28d extending across slot 38. Cooperating with iron 28d is an unattached or readily insertable and removable iron 31d having a collar portion which fits into the opening of the hat crown when the parts are assembled for operation.

As in the previous examples, it is assumed that the brim edge 43a of the hat blank is curled or rolled by a prior hand operation, but in this case preferably in the direction shown in Figure 9. Although one advantage of the method according to the present invention is that a considerable variety of brim shapes and styles may be produced in the herein described sizing and shaping procedure from hat blanks wherein the pre-roll is directed upwardly and inwardly by reference to the position of a hat when worn, the hat blank, as shown in Figure 9, more conveniently has its edge pre-curved downwardly and inwardly by reference to the position of the hat when worn. The hat blank is therefore initially placed with its brim portion 45 in position over the iron 28d and with its pre-curved edge 43a extending upwardly and inwardly. The loose iron 31d is then set in position between a ring 47 and said iron 28d and with its under or curved ironing surface resting on said brim 45.

When table 25 is moved into operative position, it brings said irons 28d and 31d with the hat brim between them to a position as seen in Figure 9 beneath iron 18c and ring 47 which are supported on frame 19b in a manner and by means of the kind shown in Figure 1, for example, whereby the iron 18 is connected to frame 19 and the latter to the ring 42 which in turn is suspended from plate 15, with springs 34 between said plate and said ring. In the modification,

Figure 10, however, ring 47 is slidably movable vertically in relation to frame 19b against the pressure of springs 36a which are stiffer or stronger than springs 35a and bears yieldingly against inner portions of the upper flat surface of iron 31d. Said iron 18c has a downwardly exposed flat pressing surface adapted in operation to cooperate with outer portions of said upwardly exposed flat surface of iron 31d. Pins 40 extending through portions of iron 18c have their inner ends projecting into vertical slots 48 in ring 47. Stop plates 49 close the upper ends of slots 48 and by engaging the inner ends of pins 40, limit the extent of downward movement of ring 47 in relation to frame 19b and iron 18c caused by springs 36a.

In utilizing the parts shown in Figures 9 and 10 for the purpose indicated, frame 19b is moved downwardly by operating lever 12 in the manner

20 previously described. Initial downward movement brings the pressure of ring 47 into operation against iron 31d to start the pressing of brim portion 45, Figure 9. Inasmuch as springs 35a are lighter or weaker than springs 36a, continued 25 downward movement of frame 19b causes irons 28d and 31d to move downwardly against yielding resistance of said weaker springs 35a. This carries the outwardly exposed curl or roll portion 43a of the brim downwardly past rim 46a of block 46 causing said curl or roll to be bent upwardly and inwardly into a position between irons 18c and 31d. Further downward movement of frame 19b continues until both sets of springs 35a and 36a are compressed fully or to a predetermined extent, or with the parts relatively positioned as shown in Figure 10. In this position, the heavy springs 34 and the heated irons exert fixing pressure on the now flattened portion of 35 43a, in a procedure analogous to that previously described in connection with Figure 4, for example.

In the forms of apparatus shown in Figures 9 and 10, the edges of the irons 18c and 31d, and of rim 46a of block 46, are preferably relieved or 45 slightly rounded to facilitate operation and to avoid injury to the hat blanks. It will be understood that the several types of irons and iron assemblies, hereinabove described as modifications, will conveniently be operated from lever 12 50 and cross head 18 in substantially the manner previously explained in connection with the types of irons shown in Figure 1; and moreover that the particular toggle press shown is not necessary to the invention but is representative of the numerous devices for applying pressure, including crank presses, screw presses, pneumatic presses, hydraulic presses, impact presses, etc.

As various embodiments may be made of the above invention and as changes might be made 60 in the embodiments above set forth, it is to be understood that all matter hereinbefore set forth or shown in the accompanying drawings is to be interpreted as illustrative and not in a limiting sense.

65 I claim:

1. The method of shaping and sizing the brim of a hat which includes the steps of bending an edge portion of the brim toward the hat crown to form a turned-in rim, applying heat and pressure to the brim between said rim and the hat crown, pressing said edge portion of said rim inwardly toward another portion of the brim while maintaining pressure on portions of the brim between the rim and the hat crown, and 70 applying heat and pressure to said inturned rim

while in said inwardly pressed position to hold said rim edge in said inturned position.

2. The method of shaping and sizing the brim of a hat which includes the steps of bending an edge portion of the brim toward the hat crown to form a turned-in rim, applying yielding pressure to the intermediate portion of the brim between said rim and the hat crown, pressing an edge portion of said rim inwardly toward said intermediate portion of the brim while maintaining pressure thereon, applying yielding pressure to said inwardly pressed portion of said rim while increasing the pressure on said intermediate portion, and applying greater yielding pressure to said rim and said intermediate portions of the brim.

3. The method of shaping and sizing the brim of a hat having a turned-in rim which includes the steps of applying initially light pressure to intermediate portions of the brim between said rim and the crown, pressuring said rim inwardly toward the hat crown while maintaining pressure on portions of the brim between the rim and the crown, applying increasing pressure to said intermediate portions, applying initial pressure to said rim portions greater than the initial pressure applied to the intermediate portions, and applying increased pressure simultaneously to said rim and said intermediate portions.

4. Apparatus for shaping and sizing hat brims having turned-in rims comprising in combination a first iron arranged and adapted to engage and press one face of those portions of a hat brim intermediate its rim and the crown, a second iron mounted to cooperate with said first iron and arranged and adapted to engage and press the opposite face of said portions, a third iron mounted to cooperate with said second iron and arranged and adapted to engage and press said turned-in rim portion of said brim inwardly, a brim perimeter size determining member mounted to cooperate with said irons and arranged and adapted to engage said turned-in rim portion when said intermediate portion of the brim is engaged between said first iron and said second iron, relatively yielding spring means operatively interposed between said first iron and said brim perimeter size determining member, spring means relatively stiffer than said yielding spring means operatively interposed between said second iron and said third iron, and means arranged and adapted to effect movement of said irons into effective pressing engagement with a hat brim.

5. Apparatus for shaping and sizing hat brims having turned-in rims comprising in combination a first iron arranged and adapted to engage and press one face of those portions of a hat brim intermediate its rim and the crown, a brim perimeter size determining member mounted in sliding engagement with said first iron, spring means operatively interposed between said first iron and said size determining member, a second iron arranged and adapted to engage and press the opposite face of said brim portions, a third iron arranged and adapted to engage and press said turned-in rim inwardly and mounted in sliding engagement with said second iron, spring means operatively interposed between said second iron and said third iron, and iron moving means arranged and adapted to effect brim and rim engaging and pressing relative movement between said irons.

6. Apparatus for shaping and sizing hat brims having turned-in rims comprising in combination, a first iron having a brim engaging surface, a second iron having a brim engaging surface spaced from and disposed opposite said first mentioned brim engaging surface, one of said irons having a rim engaging surface, a brim size determining member mounted in operative relation to peripheral portions of said first and second irons and movable in a direction across the space between said irons, a third iron mounted in operative relation to one of said first mentioned irons and having a rim engaging surface spaced from and disposed opposite said rim engaging surface of said other iron, and means arranged and adapted to actuate said irons and said brim size determining member to bring said member and said opposed surfaces of said irons into and out of brim and rim engaging relation.

7. Apparatus according to claim 6 and wherein spring means are interposed between said first and second irons and between one of said first and second irons and said brim size determining member.

8. Apparatus according to claim 6 and including spring means arranged and adapted to normally bias said third iron from one of said first and second irons, and spring means arranged and adapted to normally bias said brim size determining member from the other of said first and second irons, said actuating means including spring means operatively interposed between a movable portion thereof and said irons.

9. Apparatus for shaping and sizing hat brims having turned-in rims comprising in combination, a brim size determining member having a hollow portion, a first iron slidably mounted in telescoping relation thereto and adapted to be moved between extended and retracted positions

40 therein, said iron having an exposed brim engaging surface, spring means positioned to normally bias said iron in extended position in said hollow portion, a second iron having a brim

45 engaging surface exposed in one direction and a rim engaging surface exposed in a different direction, a third iron having a rim engaging surface exposed opposite said rim engaging surface of the second iron and mounted in telescoping sliding relation to a portion of said second iron, one of said second and third irons being movable in relation to the other to move one of said rim engaging surfaces toward and from the other, spring means positioned and

50 adapted to bias said second and third irons in a direction tending to bring one of said rim engaging surfaces away from the other, means for supporting said first and second irons with the brim engaging surface of one thereof positioned

55 opposite and in spaced relation to the brim engaging surface of the other, and actuating means for bringing said irons and said member into effective hat brim and rim engaging relation.
